UNITED STATES PATENT OFFICE.

JOHN ELDER, OF RAYMOND, ALBERTA, CANADA.

RAILROAD-SWITCH.

1,369,733.

Specification of Letters Patent. Patented Feb. 22, 1921.

Application filed May 26, 1920. Serial No. 384,245.

To all whom it may concern:

Be it known that I, JOHN ELDER, a subject of the King of Great Britain, residing at Raymond, in the Province of Alberta 5 and Dominion of Canada, have invented certain new and useful Improvements in Railroad-Switches; and I do declare the following to be a full, clear, and exact description of the invention, such as will enable 10 others skilled in the art to which it appertains to make and use the same.

This invention relates to an improved railroad switch of the ordinary type and one object of the invention is to provide a switch 15 and improved operating mechanism so constructed that the switch may be thrown for the main line or side lines and to further so construct the operating mechanism that the switch may, if desired be returned to its 20 original position after the train has passed the switch, or may be left in the set position.

Another object of the invention is to so construct this switch operating mechanism 25 that a flying switch may be made.

Another object of the invention is to so construct the operating mechanism that the switch points may be thrown by a train approaching the switch entrance from either 30 direction, thus permitting it to be operated by a train moving along the main line toward the open end of the entrance to the siding or from the opposite direction and also permit of its being operated by a train 35 which is moving along the side tracks and about to enter the main line.

Another object of the invention is to so construct this operating mechanism that it may be mounted upon the ties outside the 40 rails, instead of between the rails and to further so construct it that the levers may extend upwardly where they will be free to move and not liable to be interfered with by snow or ice.

Another object of the invention is to construct a switch operating mechanism which will be simple in construction, easy to install and not liable to readily get out of order or break.

This invention is illustrated in the accompanying drawings, wherein:—

Figure 1 is a top plan view of a track section provided with the improved operating means for the switch,

Fig. 1^A is a continuation of the structure shown in Fig. 1,

Fig. 2 is a view showing the structure of Fig. 1 in side elevation,

Fig. 2^A is a continuation of Fig. 2 and illustrates the structure of Fig. 1^A in side 60 elevation, and

Fig. 3 is a fragmentary sectional view taken along the line 3—3 of Fig. 2.

This device is used for imparting movement to the switch points 1 so that the train 65 may be directed from the main line indicated in general by the letter (M) to the side track or side line indicated by the letter (S). This main track is provided with the usual rails 2 and the side track with the usual rails 70 3 which are supported upon ties 4 in the usual manner. It will thus be seen that the railway track is of a conventional construction and it does not need a special construction of track or switch points in order to 75 permit the improved operating means to be associated therewith.

A cross bar 5 is slidably mounted transversely of the track and adjacent a foundation beam 6 and this cross bar is connected 80 with the switch points so that when the cross bar is moved transversely of the track or longitudinally of the cross bar, the switch points will be swung from one position to another and thus moved to open the main 85 line or side track according to the position to which they are moved. Locking hooks or horns 7 are pivotally mounted upon the beam 6 and are connected with the cross bar 5 by rods 8 which extend in crossed relation 90 95 as shown, so that the hooks will be swung upon their pivots when the cross bar is moved and thus the hook-shaped end portion of one of these horns moves into hooking engagement with the free end portion of one of the switch points while the shank portion of the second horn is moved into contacting engagement with the side face of the second switch point. It will thus be seen that one switch point will be held in 100 tight engagement with its coöperating rail, while the second switch point is engaged and securely held against movement toward its coöperating rails. This will prevent the switch points from being moved out of the 105 proper position by vibration and there will be no danger of one portion of a train moving into a siding and a second portion attempting to move along the main line instead of following the forward end portion 110 into the siding.

In order to impart movement to the cross

bar 5, there have been provided T-bars or levers 9 and 10 which are pivotally mounted upon the beam 6 and connected with the cross bar by pins 11 which extend through slots 5 12 in the levers 9 and 10. Treadles 13, 14, 15, 16, 17, and 18 are pivotally connected with the ties as shown in Figs. 1 and 1^A, duplicate treadles 13 and 14 being provided so that the switch points may be thrown from a 10 point distant from the side tracks or at a point relatively close to the side tracks. These treadles are of a duplicate construction and will each be formed from a strip of channel iron as shown in Fig. 3, the strip having 15 its side flanges cut away adjacent one end to provide a tongue which will be rolled to form a hinge sleeve 19 through which the bracket 20 passes to pivotally mount the treadles. These treadles will be made of a 20 sufficient length to permit a gradual incline for easy operation of the switch points and will have their free end portions curved downwardly and connected with links 21 which have their lower ends loosely connected 25 with a turning arm 22 carried by a rocker shaft 23. The rocker shaft 23 is rotatably mounted in a bearing 24 and carries an arm 25 which extends at an angle to the lever arm 22 as shown in Figs. 2 and 2^A. The two 30 treadles 13 are connected by a rod 26 which extends from the lever arm 25 of one treadle 13 and is connected with the lever arm 25 of the second treadle 13 and the two treadles 14 are connected by a similar rod 27. Rods 28 35 and 29 connect the lever arm 25 of the treadles 13 and 14 with the T-bars 9 and 10 and the T-bars are connected respectively with the treadles 15 and 16 by rods 30 and 31 and with the treadles 17 and 18 by rods 32 40 and 33. It will thus be seen that when pressure is applied to one of the treadles, movement will be transmitted to the entire operating mechanism as the switch points are moved from one position to another, movement 45 at the same time being transmitted to the switch point locking mechanism or horns mounted upon the beam 6.

In order to impart movement to the switch point operating mechanism from the train, 50 the engine 34 has been provided with a rocker arm 35 upon one side and a similar rocker arm upon the opposite side. These rocker arms 35 are yieldably held in a vertical position by springs 36 and each is engaged by a 55 rod 37 which extends into the cab where the two rods 37 may be provided with suitable actuating means. These rocker arms will each be connected with a rod 38 which is pivotally mounted and guided and limited 60 in its swinging movement by a pin 40 which extends through a curved slot 31. Arms 42 extend forwardly and rearwardly from the rocker arm or lever 39 and carry rollers 43 for engaging the treadles to depress the 65 same.

When this improved switch operating mechanism is in use, it is connected with the track as shown clearly in Figs. 1 and 1^A and if the switch points are in the position shown with the main line open and the side track 7 closed, a train approaching the switch and intending to move along the main line, will pass the switch points and proceed along the track without the operating mechanism being moved. If the train is to be broken and a 75 flying switch made, the engineer, after passing the entrance to the siding, will move the rocker arm 35 at the right hand side of the engine, thus rocking the coöperating lever 39 for engagement with the treadle 16. As the 80 engine passes over the treadle, the treadle will be pressed upon and the rod 31 will be moved to impart rocking movement to the T-bars and move the cross bar 5 thus moving the switch points to open the sidings. The 85 cars which have been released from the train and are coasting along the main line, will be diverted into the siding. A following train which is to proceed along the main line will have to set the switch to open the 90 main line and the operating means upon the right hand side of the cab or engine will be swung to the operative position so that it will engage the treadle 13 and move the rod 26 to impart movement to the T-bar or lever 95 and swing the switch points to the proper position. If the switches are set for the main line and a train is to enter the siding, the treadles 14 will be pressed upon and the cross bar 5 will be moved to set the switch 100 points for the side track. After entering the side track, the engineer may raise the treadle engaging train element to leave the side track open for a following train or he may leave the train device in the operative position 105 until after the engine has passed the treadle 15. If this is done, the treadle 15 will be moved to impart movement to the operating mechanism and the switch points will be moved to close the siding and leave the main 110 line open. It will thus be seen that a train which has the right of way may proceed along the main line with the operating mechanism of the train set to engage the treadles for moving the switches to open the 115 main line and there will be no danger of the trains running into an open siding as the switches will be moved to the proper position before the train reaches the switches. If a train is moving along the main track from 120 the opposite direction or backing along the main line or if a train is leaving a siding, the wheels of the engine will engage either the treadle 17 or the treadle 18 and set the switch points to open the main line or siding. It will thus be seen that with this improved track structure and train carried actuating means, the switches may be operated and moved to the desired position without the assistance of a switchman and with- 125 130

out it being necessary for the train to come to a stop.

What is claimed is:—

1. The combination with a track structure including a main line, a side track, and movable switch points and an operating bar for the same, of actuating mechanism for the switch points comprising a lever pivotally mounted with the bar, securing elements movably mounted, rods extending from the operating bar and connected with the securing elements for moving the securing elements into and out of an operative position as the switch points are moved, and train actuated operating means carried by the track structure and connected with the lever for imparting movement to the same and shifting the position of the switch points and securing elements.
2. The combination with a track structure including a main line, a side track and movable switch points and an operating bar for the same, of locking means for the switch points comprising horns pivotally mounted between the switch points, each horn having a curved end portion for engaging the free end portion of its coöperating switch point and having a shank extension for engaging the side of its switch point, one horn having its curved end portion engaging the free end portion of its switch point when the second horn has its shank extension engaging the side face of its coöperating switch point, means connecting the horns with the operating bar for imparting movement to the horns as the switch points are moved, and means for imparting movement to the bar.
3. The combination with a track structure including a main line, a side track, and movable switch points and an operating bar for the same, of T-bars pivotally mounted and having connection with the operating bar, actuating means positioned in the main line to one side of the switch points, actuating means in the main line upon the opposite side of the switch points, actuating means in the side track, and actuating means

in the side track and main line for setting the switch points in opposition to the last mentioned means of the side track and main line.

4. The combination with a track structure including a main line, a side track, switch points, and a cross bar connecting the switch points, of means for imparting movement to the switch points including pivotally mounted T-bars having connection with the cross bar, actuating elements mounted upon opposite sides of the main line in advance of the switch points, rods connecting the actuating elements with the inner end portions of the T-bars, actuating elements mounted in the main line beyond the switch points, actuating elements mounted in the side track beyond the switch points, rods connecting certain of the actuating elements of the side track and main line with the inner end portions of the T-bars, rods connecting the remaining actuating elements of the side track and main line with the outer end portions of the bars.

5. The combination with a track structure including a main line, a side track, switch points, and a cross bar connecting the switch points, of operating means for the switch points including levers connected with the cross bar, means upon one side of the main line connected with one of the operating levers to move the cross bar to set the switch points in one position, means upon the opposite side of the main line and connected with a second lever for moving the cross bar to position the switch points in a set position, means mounted adjacent the main line and side track and connected with the levers for imparting movement to the same reversely to the movement imparted by the first and second mentioned means, and other means mounted adjacent the side track and main line and connected with the levers for imparting movement to the same.

In testimony whereof I have hereunto set my hand.

JOHN ELDER.
